UNITED STATES PATENT OFFICE.

HARRY O. RASTETTER, OF CANTON, OHIO, ASSIGNOR TO THE UNION METAL MANUFACTURING COMPANY, OF CANTON, OHIO, A CORPORATION OF OHIO.

REINFORCED-METAL TUBE.

Application filed July 19, 1921. Serial No. 485,831.

To all whom it may concern:

Be it known that I, HARRY O. RASTETTER, a citizen of the United States, residing at Canton, in the county of Stark and State 5 of Ohio, have invented a new and useful Reenforced-Metal Tube, of which the following is a specification.

This invention relates to reenforced metal tubes, and has for its objects to provide 10 a metal tube arranged to support a load or to receive strains or stresses, and provided with interior reenforcing means arranged to prevent buckling or bending of the tube, due to the weight or strain placed thereon, 15 and to prevent the tube from being bent or buckled by an impact or blow against any side of the tube.

The above and other objects may be attained by providing a sheet metal tube of 20 any desired cross sectional shape and reinforced by a plurality of radial vanes or webs preferably surrounding a central rod or tube and engaging the inner wall of the tube at spaced intervals.

25 Although the invention is adaptable to any form of metal tube, it is designed especially for use upon hollow sheet metal columns such as are used for building purposes and for lamp standards for street and park lighting and the like.

The invention thus set forth in general terms is illustrated in the accompanying drawings, in which—

Figure 1 is a vertical, sectional view 35 through the lower portion of a lamp standard provided with a hollow sheet metal column embodying the invention;

Fig. 2, a perspective view of a portion of the lamp standard with the tubular shell 40 removed, showing the reenforcing vanes in position upon the base of the column;

Fig. 3, a perspective view of the base of the column showing the tie rods broken off with the reinforcing vanes removed from 45 the base;

Fig. 4, a transverse, sectional view on the line 4—4, Fig. 1;

Fig. 5, a perspective view of a tube provided with wide ribs or flutes showing the 50 reenforcing vanes engaging the flutes or ribs.

Fig. 6, a section on the line 6—6, Fig. 5;

Fig. 7, a perspective view of a round tube 55 or column with the same form of reenforcing vanes as illustrated in Fig. 5;

Fig. 8, a perspective view of the reenforcing vanes assembled upon the central rod or tube, such as shown in Figs. 5 to 7 inclusive;

Fig. 9, a cross sectional view through a 60 fluted column, such as shown in Fig. 1, showing a slightly different form of reenforcing vanes;

Fig. 10, a similar view showing a still further modification of the reenforcing 65 vanes;

Fig. 11, a cross sectional view through a round tube showing a different construction of reenforcing vanes;

Fig. 12, a cross sectional view through a 70 hexagonal tube showing an arrangement of reenforcing vanes somewhat similar to that shown in Fig. 8;

Fig. 13, a cross sectional view through a 75 fluted column showing a further modification of the reenforcing vanes;

Fig. 14, a cross sectional view through a triangular tube or column, showing a different form of reenforcing vanes;

Fig. 15, a cross sectional view of a fluted 80 tube or column showing the reenforcing vanes extending into the flutes of the tubular member, the central rod being dispensed with;

Fig. 16, a perspective view of a further 85 modification of the invention, showing the same applied to a tapered column, parts being broken away for the purpose of illustration;

Fig. 17, a vertical, sectional view through 90 the same upon an enlarged scale taken on the line 17—17, Fig. 18;

Fig. 18, a transverse, sectional view taken 95 upon the line 18—18, Fig. 17; and

Fig. 19, a detail perspective view of one 100 of the reenforcing rings shown in Figs. 16 to 18 inclusive.

Similar numerals of reference indicate corresponding parts throughout the several figures of the drawings.

Referring first to Figs. 1 to 4, inclusive, in which the invention is shown applied to a shaft or column, designed to carry an illuminating lamp, the base of the column is shown at 1, and is preferably cast. This base, as shown, is hollow and may be of any suitable and well known construction, and is provided at its upper end with the concentric, annular shoulder 2, upon which is located the lower end of the tubular sheet 105 110

metal column 3. This construction is common in lamp standards of this character, as shown in Patent No. 1,086,346, in which the tubular sheet metal column is mounted upon the base in this manner.

- Where a hollow metal column of this character is used in a lamp standard placed along a street or roadway, or in a similar location where the column is likely to be struck by passing vehicles, it has been found that some reenforcement is necessary for the hollow metal column, as in cases where vehicles have collided with a column of this description, the column has been collapsed, throwing the lower end of the same out of engagement with the annular shoulder upon the base, making it necessary to tear down the entire structure and replace or repair the hollow metal column.
- 10 The purpose of the present invention is to provide a reenforcing means for a hollow, sheet metal column or tube, which will prevent collapsing of the column or tube in the manner above described, and which will 15 eliminate the possibility of a hollow metal column used in a lamp standard from being damaged to such extent as to require the standard to be torn down and the column repaired or replaced.
- 20 The reenforcing means shown in Figs. 1 to 4 inclusive includes a central rod 4 around which are located a plurality of radially disposed vanes 5 and 6, the vanes 6 extending entirely across the interior of the column and engaging oppositely disposed flutes 7 of the column, each of said vanes being 25 provided with a vertical, half round recess 8, which receives the rod 4, the vanes 5 each extending from the adjacent portion 8 to 30 one of the flutes 7 of the column. A disk 9 is located at each end of the rod 4 and clamps against the upper and lower ends of the vanes 5 and 6 by means of the nuts 10.
- 35 The tie bolts 11 are connected beneath the base in any suitable manner, such as by embedding the same in the cement 12 as shown in Fig. 1, and extend through suitable apertures in the lower disk 9 and between adjacent vanes as best shown in Fig. 4, the upper 40 threaded ends thereof extending through suitable apertures in the upper disk 9, nuts 12 being provided upon the upper ends of said tie bolts for clamping the upper disk tightly upon the reenforcing vanes and 45 drawing the vanes into tight engagement with the lower disk 9 which is thus clamped against the annular shoulder 2 of the base.
- 50 Tie rods 13 may be connected to the upper portion of the base as shown in Figs. 1 and 3 and extend upwardly between adjacent vanes and through suitable apertures in the upper disk 9, for the purpose of attaching the capital of the column in the same manner as shown in the patent above referred to.
- 55 In Figs. 5 to 8 inclusive the reenforcing

means comprises a central rod or tube 14 to which the vanes 15 are connected, said vanes being made in pairs, a curved connecting strip 16 being formed upon each pair and shaped to conform to the curvature of the central tube 14, rivets 17 or the like being passed through said connecting strips for attaching the vanes to the central rod or tube.

60 In Fig. 5 this form of reenforcement is shown in a fluted column 18, one vane extending into each flute 19 of the column, while in Fig. 7, a round column or tube is shown, the outer vertical edges of the vanes engaging the inner wall of said tube or column.

65 In Fig. 9 is shown a cross sectional view of a fluted column or tube 21 in which one vane 22 is provided with a vertical, tubular portion 23 extending around the central rod 24, the remaining vanes 25 engaging said tubular portion at their inner edges, said vanes, the same as shown in Fig. 4, being of sufficient thickness to be held in engagement with the inner edge portions of the adjacent vanes when the device is assembled, the outer edge portions of all of the vanes extending into the flutes 26 of the tube or column.

70 In Fig. 10 the fluted column or tube 27 is provided with the concentric shaft or tube 28, the vanes 29 being formed in pairs and each provided with a vertical connecting strip 30 which may be attached to the central tube 28 in any desired manner, the outer edges 31 of said vanes extending into the flutes 32 of the column or tube 27.

75 The round tube or column 33 shown in Fig. 11, is provided with the central, cross sectionally X-shaped rod 34, the vanes 35 engaging the inner wall of the tube at their outer edges, the inner edges thereof being located between the ribs 36 of the rod 34.

80 In Fig. 12 is shown a hexagonal column 42 having a central rod 43, the vanes 44 being formed in pairs, each pair having a connecting strip 45 which is attached to the rod 43 in any suitable manner, the outer edges of the vanes extending into the corners 46 of the column 42.

85 A fluted tube or column 37 is shown in Fig. 13, a concentric tube 38 being located therein. Each of the vanes 39 is T-shaped in cross section, the head portions 40 thereof engaging the inner tube 38 and being of sufficient width to engage the head portions of adjacent vanes upon each side, the outer edge portions of the vanes extending into the flutes 41, of the outer tube or column 37.

90 In Fig. 14, the invention is shown adapted to a triangular tube or column 47, a hexagonal rod 48 extending through the center thereof. The vanes are formed in pairs, a long vane 49 and a short vane 50 being connected in each pair by means of a connecting

strip 51 which is attached to the rod 48 as by the rivets 52, the outer edge of the long vane engaging the adjacent corner 53 of the column, while each short vane engages the central portion of one of the side walls 54 thereof.

A hexagonal tube or column is shown in Fig. 15 and designated by the numeral 55, the vanes 56 and 57 being located obliquely 10 through the tube and engaging the inner corners thereof. Any suitable construction of the vanes may be provided, such as the form illustrated, in which the vane 56 extends entirely across the tube, while each 15 vane 57 extends from the adjacent corner of the tube to the vane 56, being connected thereto.

It may be found desirable in some instances to locate a crimped wire 58 at intervals around the vanes to hold the outer edges of the same in proper spaced relation, and to hold the entire reinforcing structure assembled until the same is placed within the tube or column.

25 Referring to Figs. 16 to 19, inclusive, in which a further modification of the invention is shown applied to a tapered column, such as might be used for supporting a lamp or the like, the base, which is preferably cast, is shown at 60, and may be provided with the annular shoulder 61, over which the lower end of the tapered, fluted, metal column 62 is placed, said base being provided with the tapered, annular flange 35 63.

The reinforcing vanes in this form of the invention are preferably in the shape of U-bars 63', the flanges or vanes 64 thereof being radially disposed and extend into the 40 flutes 65 of the metal column 62.

Annular reinforcing members are located at intervals within the U-bars, these annular members being slightly tapered to conform to the taper of the column. These reinforcing members may be in the form of rings such as shown at 66 having a reinforcing spider 67 therein, the U-bars being connected to said rings as by the rivets 68.

The lower reinforcing member may, if 50 desired, be elongated in the form of the tapered tube 66' extending from the base upwardly a suitable distance to reinforce the portion of the column which may be subjected to blows.

55 The lower end of the reinforcing tube 66' may be located around the tapered flange 63 of the base to further reinforce the lower end of the structure.

The upper reinforcing ring 66' is preferably extended around the downwardly disposed, tapered flange 69 of the top plate 70, said flange also engaging the inner surfaces of the U-bars at their upper ends.

65 The top plate 70 is clamped firmly upon the upper ends of the U-bars and the column

62 by means of tie bolts 71 which pass downwardly through the annular reinforcing members and through lugs 72 provided in the base 60, nuts 73 and 74 being provided at the lower and upper ends of said tie 70 bars for drawing the parts together, thus clamping the column and the U-bars firmly upon the base.

From the above, it will be seen that numerous modifications of the invention 75 may be provided, in all of which a central rod or tube is surrounded by radial vanes engaging the inner wall of the hollow column or tube, means being provided for preventing movement of the inner edge portions of the vanes, and flutes or the like being provided in the tube or column in most of the modifications, into which the outer edge portions of the vanes extend to prevent relative movement of the outer 80 edges of the vanes with reference to the tube or column.

It will be evident that with the provision of a reinforcement such as above described, 85 it will be practically impossible to collapse a sheet metal column or tube in the manner above referred to, as the reinforcing vanes will strengthen the hollow column and prevent the same from being seriously damaged.

It is of course understood that hollow fluted sheet metal columns of the type shown in the drawings are at present placed upon a mandrel, rollers being passed over the column for forming the flutes therein but it will be obvious that the mandrel will be dispensed with, the reinforcing vanes being inserted in the cylindrical column, such as shown in Fig. 7, the column being supported in the forming machine upon the reinforcing vanes, the flutes being formed over the edges of the vanes, as indicated by dotted lines in Fig. 7, the finished column formed in this manner being shown in Fig. 5.

I claim:—

1. An article of manufacture, including a fluted, sheet metal, tubular member, and a plurality of radial reinforcing vanes located therein and extending into said flutes.

2. An article of manufacture, including a fluted, sheet metal, tubular member, a central member extending therethrough and a plurality of radial reinforcing vanes engaging said central member and extending into 115 said flutes.

3. An article of manufacture, including a fluted, sheet metal, tubular member, a central member extending therethrough and a plurality of radial vanes within the tubular member and extending into the flutes thereof, one of said vanes having a curved portion extending around the central member.

4. An article of manufacture, including a base, a hollow, sheet metal column mounted thereon, a plurality of radial vanes en- 120 125 130

gaging the inner wall of the column, and means for connecting said radial vanes to the base.

5. An article of manufacture, including a base having a shoulder at its upper end, a hollow, metal column mounted upon said shoulder, a plurality of radial vanes engaging the inner wall of the column, a plate engaging each end of said vanes and 10 rods extending upwardly through the base and through said plates.

6. An article of manufacture, including a base having a shoulder at its upper end, a hollow, metal column mounted upon said 15 shoulder, a plurality of radial vanes engaging the inner wall of the column, a plate engaging each end of said vanes and rods extending upwardly through the base and through said plates, the lower plate engaging the upper end of the base.

7. An article of manufacture, including a base having a shoulder at its upper end, a hollow, metal column mounted upon said shoulder, a plurality of radial vanes 25 engaging the inner wall of the column, a plate engaging each end of said vanes and rods extending upwardly through the base and through said plates, and means upon the upper ends of the rods for clamping the 30 plates upon the ends of the vanes and clamping the lower plate upon the upper end of the base.

8. An article of manufacture, including a base having a shoulder at its upper end, a fluted, hollow, metal column mounted upon 35 said shoulder, a plurality of radial vanes within the column and extending into the flutes thereof; a plate at each end of said vanes, and tie rods extending upwardly through the base and through said plates 40 and provided with means for clamping the plates upon the vanes and holding the lower plate in engagement with the upper end of the base.

9. An article of manufacture, including 45 a base, a fluted, hollow, metal column mounted upon said base, a plurality of radial vanes extended into said flutes, annular reinforcing members connected to the inner edges of said vanes at spaced intervals, a 50 plate mounted upon the upper end of the column and engaging the upper ends of the vanes and tie rods located between the base and said plate for drawing the column and vanes into engagement with the base. 55

10. An article of manufacture, including a tubular member having longitudinal corners, and a plurality of radial reinforcing vanes located therein and extending into 60 said corners.

In testimony that I claim the above, I have hereunto subscribed my name.

HARRY O. RASTETTER.
